UNITED STATES PATENT OFFICE.

MARCOLINA DOMENICO, OF PHILADELPHIA, PENNSYLVANIA.

AUTOMATIC TIE-HOLDER FASTENER.

Application filed January 30, 1925. Serial No. 5,875.

To all whom it may concern:

Be it known that I, MARCOLINA DOMENICO, a citizen of the United States, residing at Philadelphia, in the county of 5 Philadelphia and State of Pennsylvania, have invented new and useful Improvements in Automatic Tie-Holder Fasteners, of which the following is a specification.

This invention relates to improvements in 10 tie holding means and contemplates the provision of means included in the knot of a four-in-hand tie which may be easily and readily applied to the front collar button stud.

15 Another object of the invention is the provision of means included in the fastener whereby slight pressure on the end portions thereof will expand the fastener in order that the same may be spread so that the 20 same may be positioned over or removed from the forward stud portion of the front collar button.

A further object of the invention is the provision of stud members mounted upon 25 the outer end portions of the fastener and which are adapted to extend through button-holes arranged in a soft collar whereby the same will hold the collar toward the neck as well as provide means for operating 30 the fastener and provide a very neat appearance to the collar.

With the above and other objects in view, the invention further includes the following 35 novel features and details of construction, to be hereinafter more fully described, illustrated in the accompanying drawing and pointed out in the appended claims.

In the drawing:

40 Figure 1 is a front elevation of a soft collar showing the present invention applied thereto with the four-in-hand tie looped thereover.

Figure 2 is a top plan view of the invention.

45 Figure 3 is a similar view of a modification of the invention.

Figure 4 is an end elevation of the preferred form of my invention.

Referring to the drawing in detail, 50 wherein like characters of reference denote corresponding parts, the reference character 10 indicates a collar which is preferably of a soft or semi-soft material and which has button-holes included upon opposite end portions thereof which is of the usual and well known construction or type and forms

no part of the present application nor in combination with the four-in-hand tie 11 which are merely shown for purposes of illustration in bringing forward the purposes 60 and advantages of the above entitled application.

Referring to Figures 1 and 2 of the drawing wherein the preferred form of my invention is shown I provide a singular length 65 of rust proof wire which is bent or curved intermediate the length thereof as at 12 and which has its opposite end portions extending upwardly and outwardly and looped as at 13. These loops 13 in turn 70 have their opposite end portions extending rearwardly and back of the curved portion 12 and meet each other or intersect as at 14 and are then reversely curved outwardly as at 15 and provide arcuate shaped portions 75 16 while the outer end portions of the wire include stud member 17 thereon which are adapted to be inserted within the button-holes provided in the soft collar 10 whereby the outer flap of the collar will be held inwardly toward the inner flap in order to provide a neat appearance of the collar. It will also be noted that upon pressure, stress or exercise upon the stud member 17 that the looped or arcuate shaped portion 16 will 80 be caused to be spaced apart in order to allow the forward stud portion, not shown, of a collar button, not shown, to be inserted therein and upon the release of the 85 stud member 17 it will be noted that the arcuate shaped portion 16 will engage the shafts, not shown, of the collar button, not shown, in order that the device may be securely held to the collar and in proper 90 position through the instrumentality of the 95 stud members extending through the button-holes of the collar 10.

When applying a tie such as shown at 11 in Figure 1 of the drawing to this invention it will be clearly apparent that upon taking the tie and putting the end portions together and then taking the upper portions of the two lengths and positioning them over the loop 13 it will be noted that one portion of the tie will extend across the intermediate 100 portion 12 and that the stud members will 105 extend rearwardly of the tie.

Referring to Figure 4 of the drawing wherein a modification of my invention is shown, I include the identical structure of 110 the preferred form save hook members 17 as shown positioned on the preferred form

of the invention in Figure 2 of the drawing; in this form of the invention I extend the free end portion of the wire outwardly and loop them upon themselves as at 18 and 5 which loop portions may be stressed as the stud portion 17 and it will also be apparent that this form of the invention is to be applied to stiff collars and the loop portions 18 are adapted to lie flush with the outer 10 side of the inner flap of the collar as there are no button-holes provided in stiff collars.

It will be noted that owing to the simple and novel construction of the fastener that the same may be manufactured in great 15 numbers and consequently sold at a very nominal cost and will provide a very efficient and effective tie holding fastener which owing to the novel form of attaching means to the stud of a collar button that the same 20 may be securely held thereto against accidental displacement and prevent wear of the ties as they are merely looped upon themselves over the looped portions 18 of the fastener and consequently are not rubbed 25 owing to constant tying and pulling when tying a four-in-hand knot. Owing to the nominal cost of these fasteners a tie may be tied upon each of the fasteners and held on a rack whereby the ties may be taken 30 down and readily and easily applied to the collar.

The invention is susceptible of various changes in its form, proportions and minor 35 details of construction, and the right is herein reserved to make such changes as properly fall within the scope of the appended claims.

Having thus described my invention what is claimed is:

1. As a new article of manufacture, a 40 single length of wire being curved upon itself intermediate the length thereof and having its opposite end portions curving upwardly and outwardly and looped, these looped portions extend rearwardly and 45 downwardly and are reversely intersected, and stud members formed on the outer end portions thereof.

2. An automatic tie holder and fastener of the character described comprising a 50 single length of wire having its intermediate portions curved downwardly and providing upwardly and outwardly extending looped portions therefrom; the opposite end portions extending downwardly and 55 rearwardly therefrom and providing arcuate shaped intersecting portions thereon, stud members formed on the outer end portions of the wire whereby upon the stressing of the stud members the said arcuate shaped intersecting portions may be spread in order that the same may receive the stud portion of a collar button therein.

3. A tie holder fastener of the character described comprising a single length of wire having its intermediate portion curved downwardly and having the opposite end portions thereof extending upwardly and outwardly therefrom and looped upon themselves, the opposite end portions thereof extending downwardly and rearwardly therefrom and providing reversely intersecting arcuate shaped looped portions thereon, and looped portions formed on the free end portions of the wire and in direct alignment 70 with the lengths thereof.

In testimony whereof I affix my signature.
MARCOLINA DOMENICO.
